SKI TOW ROPE RELEASE

Rollow D. Kimball, 2647 Hall Circle, Kearns, Utah
 Filed Nov. 9, 1964, Ser. No. 409,693
 10 Claims. (Cl. 114—235)

This invention relates to releasable safety couplings for rope and the like and more particularly relates such couplings for use in water skiing for releasing the tow rope from the skier when falling in the water.

In water skiing, the skier and particularly the beginner when falling in the water does not release the tow rope before being dragged along the water by the rope. This increases the impact of the fall and frequently results in the skier becoming tangled in the tow rope. While little if any injury will occur if the skier releases his grip on the tow rope as he starts to fall, the impact of the fall is materially increased when the rope is not released and this impact together with the pulling of the skier along the water after having fallen, or the tangling of the rope with the skier, frequently results in serious injury to the skier.

The present invention has as its principal objects to remedy this difficulty by providing a safety coupling in the tow rope, releasing the tow rope from the skier the instant the coupling hits the water, as the skier is falling.

Another object of the invention is to provide an improved form of ski tow rope having a releasable coupling therein maintaining a continuous tow line from the boat to the skier and releasing the tow line from the skier upon impact of the coupling with the water.

Still another object of the invention is to provide a coupling adapted to be placed in water ski tow lines adjacent the skier, in which coupling and socket members are retained in engagement with each other by a simplified form of axial clutch, and in which a release member is provided for the clutch, releasing the clutch upon engagement of the release member with the water.

A still further object of the invention is to provide a form of tow rope safety release placed in a ski tow rope adjacent the skier including a socket member connected to one part of the rope and a coupling member registrable with the socket member and connected to an adjacent end portion of another part of the rope, in which an axial clutch is provided to hold the coupling and socket members from axial movement with respect to each other and a cup-like release member maintains the clutch in an engaged position and releases the clutch by the reaction of the water against the release member as the tow rope is under load, to instantaneously release the coupling member from the socket member.

These and other objects of the invention will appear from time to time as the following specification proceeds and with reference to the accompanying drawing wherein:

FIGURE 1 is a diagrammatic plan view of a water ski tow rope release constructed in accordance with the principles of the present invention showing the release in a tow rope attached to a boat and positioned adjacent the portion of the tow rope grasped by the skier;

FIGURE 2 is a longitudinal sectional view taken substantially along line II—II of FIGURE 1;

FIGURE 3 is a view somewhat similar to FIGURE 2 but showing the coupling in a released position;

FIGURE 4 is a transverse sectional view taken substantially along line IV—IV of FIGURE 2; and

FIGURE 5 is a transverse sectional view taken along substantially line V—V of FIGURE 4.

In the embodiment of the invention illustrated in the figures of the drawing, I have diagrammatically shown in FIGURE 1 a portion of a boat 10, which may either be an inboard or outboard motor boat having a ski rope 11 connected thereto having a releasable safety coupling 12

2

connected to its end. The releasable coupling 12 forms a coupling member connecting the ski tow rope 11 with a rope portion 13 branching off to a yoke 15 connected to a hand grip bar 16, adapted to be grasped by the hand of the water skier. The rope 11, the yoke section 15 and the hand grip bar 16 are conventional elements so need not herein be described further.

The safety coupling 12 may be made from a plastic material, or of any other material sufficiently strong to withstand the pull of the tow rope, and includes a coupling member or plug 17 having a central hole 18 extending axially therealong for a portion of the length thereof communicating with a molded or cross-drilled hole 19. In attaching the coupling member 17 to the tow rope 11, the rope is passed through the axial hole 18 and out through the hole 19. A knot 20 may then be tied to the end of the rope to retain the coupling member to the rope. The coupling member 17 has a reduced diameter outer end portion 21 fitting within a socket 22 of a socket member 23. The socket member 23 has a drilled or molded hole 24 extending axially into the socket 22 from the outer end thereof to receive the rope 13. The rope 13 is passed through the socket 22 beyond the end thereof and knotted as indicated by reference character 25 and is then drawn outwardly with the knotted portion 25 in engagement with the base of the socket 22 to retain the rope portion 13 to the socket member 23.

The coupling member 17 is retained to the socket member 23 to provide a solid coupling between the rope sections 11 and 13 to raise the skier to the surface of the water and retain the skier to the surface of the water by travel of the boat by a releasable axial clutch 27, herein shown as being a ball type of clutch and locked in position by a release member 29 slidable along a reduced diameter portion 30 of the socket member 23.

As shown in the drawings, the clutch 27 includes a plurality of hardened balls 31 radially slidable along radial apertured portions 33 of a sleeve end portion 35 of the socket member 23 of a reduced diameter from the diameter of the reduced diameter portion 30 and terminating in a shoulder 36 forming a seat for a spring 37. The balls 31 releasably engage an outwardly opening annular groove 39 formed in the reduced diameter portion 21 of the coupling member 17 and are retained in locking engagement with said groove by cylindrical engaging face 40 of the release member 29 slidable along the sleeve portion 35. The spring 37, seated on the shoulder 36 at one end, is seated on a shoulder 41 of the release member 29 at its opposite end, and maintains the cylindrical engaging face 40 over the balls 31, to normally maintain the balls in the groove 39 to form a solid coupling between the members 17 and 23 and rope sections 11 and 13.

The release member 29 has a hub portion 43 slidable along the reduced diameter portion 30 and sleeve portion 35 of the socket member 23. The hub portion 43 has an inner or front wall 44 facing in the direction of travel of the ski rope and extending radially outwardly therefrom and terminating in a frusto-conical wall 45 flaring outwardly to a cylindrical wall 48, opening to the advance end of the release member and forming in effect a cup opening in the direction of travel of the skier and providing the reaction when engaging the water, as the skier falls, to effect movement of the release member against the spring 36 and release the annular retaining surface 40 from the balls 31, to accommodate the release of the coupling member 17 from the socket member 23.

It may be seen from FIGURE 2 that in the release position, the balls pass into an enlarged diameter portion 46 of the release member to accommodate free movement

of the coupling member 17 out of the socket member 23. A snap ring 47 is snapped into engagement with the inner end of the socket member 23 to engage the shoulder defining the inner margin of the enlarged diameter portion 46 and retain the socket member 23 to the release member 29, to enable the coupling to be again connected to effect a solid coupling member for a next succeeding water skiing operation.

In using the releasable tow rope coupling, assuming the rope sections 11 and 13 are attached to the respective coupling and socket members 17 and 23, it is merely necessary to insert the reduced diameter portion 21 of the coupling member 17 into the socket 23 into engagement with the wall 44 of the release member 29. The spring 37 will then bias the release member 29 into engagement with the shoulder of the coupling member and the cylindrical wall 40 will retain the balls 31 in the groove 39 and hold the coupling and socket members in connected relation with respect to each other. In skiing, all that is necessary is for the skier to grasp the tow bar 16 and hold the coupling member 12 out of the water, it being understood that the coupling member is closely adjacent the skier and will normally be out of the water when the skier's hands are out of the water in position to be towed and there is tension on the tow rope. The skier may then be pulled by the tow rope to the surface of the water in a customary manner and the rope sections 11 and 13 will be a continuous rope during the normal skiing operation. If, however, the skier should fall, the cup-like portion of the release member 29 reacting against the water as the coupling member 17 and cup-like member 29 are pulled by the tow rope in the direction of travel of the boat, the release member 29 will move against the bias of the spring 37 to move the annular retaining surface 40 away from the balls 31 of the clutch 27. The balls 31 moving radially outwardly by the reaction between the coupling member 17 and the socket 23 will move outwardly to the enlarged diameter portion 46 of the release member and instantaneously release the coupling member from the socket member and free the skier from the tow rope and boat.

It should here be understood that the releasable coupling 12 may be made from materials which will float in water although it need not necessarily be made from such materials. The members of the coupling also may be hollow to provide air spaces therein to cause the coupling to more readily float to enable the sections of the coupling to be readily retrieved. The hollow structure, however, is no part of the present invention so need not be shown or described herein.

While I have herein shown and described one form in which the invention may be embodied, it should be understood that various variations and modifications in the invention may be attained without departing from the spirit and scope of the novel concepts thereof.

I claim as my invention:

1. A release for water ski tow ropes particularly adapted to release the tow rope from the skier comprising:

a coupling member,

a socket member,

means retaining said coupling and socket members in coupled relation with respect to each other including a movable release member mounted on one of said members and movable axially of said members upon engagement of said release member with the water, to accommodate separation of said members and the freeing of the skier from the tow rope.

2. A release for tow ropes particularly adapted to free the water skier from the tow rope when falling in the water comprising:

a socket member,

a coupling member adapted to fit in said socket member,

interengaging axial clutch means retaining said coupling member to said socket member, and

5 a release member retaining said clutch means in position to provide a solid coupling between said members and releasing said clutch means and effect the separation of said members by the reaction of said release member with the water as the skier falls when being pulled by the tow rope.

3. A tow rope release in accordance with claim 2 in which the release member is slidably movable along the socket member, wherein spring means bias the release member along the socket member in position to maintain a rigid coupling between the coupling member and socket member and wherein the release member has a cup-like advance end portion facing in the direction of travel of the skier providing the necessary reaction to move said release member against said spring by the reaction of the water against said release member as the skier falls during a skiing operation.

4. In a tow rope release particularly adapted for releasing water skiers from the tow rope when falling,

20 two aligned tow rope sections,

a socket member connected to one tow rope section, a coupling member connected to a second tow rope section and adapted to fit within the socket member, an axial clutch holding said members from axial movement with respect to each other and including a clutch member adapted to have interengaging connection with said members,

30 a release member movably mounted on one of said members for maintaining said clutch member in an engaging position and for accommodating the release of said clutch member to effect disconnection of said members,

means biasing said release member in a clutch engaging position,

35 said release member being moved against its spring bias by its reaction against the water as the towed water skier falls, to effect the release of said clutch member and the axial separation of the two aligned sections of the tow rope.

40 5. A tow rope release in accordance with claim 4 wherein spring means bias the release member into a clutch engaging position and wherein the release member has a cup-like advance end portion opening in the direction of travel of the ski rope and providing the reaction to effect movement of said release member against said spring and thereby release the clutch as the skier falls and said coupling means into engagement with the water.

6. In a tow rope release particularly adapted to release the tow rope from a water skier being pulled thereby, in which the tow rope includes,

50 two aligned rope sections connected between the boat and skier,

a socket member connected to one rope section,

a coupling member connected to a second rope section and adapted to fit within said socket member,

55 a plurality of clutch members movably carried by said socket member for engagement with said coupling member to couple said coupling member to said socket member,

a release member mounted for movement along said socket member and engaging said clutch members and retaining said clutch members in engagement with said coupling member,

60 spring means biasing said release member in a direction to retain said clutch members in engagement with said coupling member, and said release member having an enlarged forward end portion affording the reaction when engaged with the water as the tow rope is pulling the skier, to move said release member along said socket member out of clutch engaging position and to accommodate the axial release of said clutch members from said coupling member and free the skier from the tow rope when falling.

7. A tow rope release in accordance with claim 6 wherein the clutch members are in the form of balls guided in the socket member for radial movement with respect thereto.

8. In a water ski tow rope, a rope section having an end adapted to be connected to a boat and having an opposite free end,

an axially aligned second rope section forming a continuation of said first mentioned rope section and having a hand grip on the outer end thereof adapted to be grasped by the skier,

an axially releasable coupling connecting said rope sections in end-to-end relation with respect to each other and including a release member movable along the coupling and biased into position to form a positive coupling between said rope sections and having an enlarged forwardly facing open end portion engaging the water upon falling of the skier and moved by the force of the water into a release position to effect release of the coupling.

9. In a water ski tow rope, a rope section having an end adapted to be connected to a boat and having an opposite free end,

a second axially aligned rope section forming a continuation of said first rope sections and having a hand grip thereon adapted to be grasped by the skier,

an axially releasable coupling connecting said rope sections in end-to-end relation with respect to each other comprising a coupling member connected to the free end of said first mentioned rope section and having a generally cylindrical reduced diameter advance end, a socket member connected to the second rope section and having a generally cylindrical socket therein

5

adapted to receive said reduced diameter advance end of said coupling member, said reduced diameter advance end of said coupling member having an outwardly opening annular groove therein within the confines of said socket member when said coupling is engaged, said socket member having radial apertured portions registering with said groove when said coupling member is in an extreme inwardly extended position with respect to said socket member, clutch balls carried by said apertured portions of said socket member for engagement with said groove, a release member slidably mounted on said socket member and having an internal cylindrical wall portion maintaining said balls in engagement with said groove, spring means biasing said internal cylindrical wall portion into engagement with said balls to maintain said coupling in a connected condition, and said release member having an enlarged area portion extending radially outwardly of said coupling member providing the reaction against the water as the skier falls and the coupling member is pulled into the water, to move said release member against its spring bias and effect release of the clutch.

10. A water ski tow rope in accordance with claim 9 in which the enlarged area portion of the release member is of a cup-like shape opening in the direction of travel of the ski rope.
